Robert Burns

Attorney.

UNITED STATES PATENT OFFICE.

GEORGE KELLY, OF CHICAGO, ILLINOIS.

EQUILIBRIUM APPLIANCE FOR ROCKING-CHAIRS.

SPECIFICATION forming part of Letters Patent No. 379,472, dated March 13, 1888.
Application filed October 18, 1887. Serial No. 252,743. (No model.)

To all whom it may concern:

Be it known that I, GEORGE KELLY, a citizen of the United States, and a resident of Chicago, in the county of Cook and State of Illinois, have invented a certain new and useful Improved Equilibrium Appliance for Rocking-Chairs and Like Articles; and I do hereby declare the following to be a full, clear, and exact description of the same, reference being had to the accompanying drawings, forming a part of this specification.

This invention relates to that class of household and other articles, such as rocking-chairs, swings, and similar exercising and comfort-giving articles; and the object of the present improvement is to provide an improved equilibrium or equalizing attachment for use in connection with the aforesaid articles, so as to render the swinging or rocking motion of the same constant, uniform, and light-running. I attain such object by the mechanism illustrated in the accompanying drawings, in which—

Figure 1 is a side elevation of an ordinary rocking-chair to which my improved appliance is attached; Fig. 2, a detail side view of a rocking-chair illustrating a modified form of my improvement; Fig. 3, a detail section of a modified form of my improved appliance; and Fig. 4, a detail elevation, illustrating the adaptation of my improvement to a platform rocking-chair.

Similar letters of reference indicate like parts in the several views.

As represented in the drawings, my improved equilibrium or equalizing device consists of a horizontally-arranged track tube or box, A, containing a shifting body or weight, B, which shifts from end to end of the box or track as the same is swung out of a horizontal plane.

The shifting body or weight may be in the form of a body of mercury or other fluid, as indicated in Figs. 1, 2, and 4, or that of a globe, as indicated in Fig. 3. In the latter case the track-tube A will be provided with cushion-springs C, of any well-known form, at each end, to receive the impact of the globe or ball and assist in imparting a return movement to the same.

The form of the track tube or box A may be either straight, as shown in Figs. 1 and 2, or

of a curved form, as shown in Fig. 4, as the circumstances or special use of the device may suggest.

In case where a very long track tube or box A is required I prefer to form the bottom of the same inclined upward from each end to the center, (see Fig. 3,) and provide in connection therewith a duplicate arrangement, B B', of the shifting weight or balls, as indicated in Fig. 3, which act respectively to and from the middle of the track or tube, and not from end to end of the same, as hereinbefore described.

My improved device is intended for attachment to the side of a rocking-chair, either fixedly, as indicated in Fig. 1, or capable of a slight horizontal movement in guides, as indicated in Fig. 2; or it may be arranged in or form one or both of the rockers C of the chair, as indicated in Fig. 4, such arrangement being specially adapted to platform rocking-chairs; and with such application it is preferred to use cushion-springs D, attached at either or both ends of the platform D', and adapted to bear under the end or ends of such rocker to assist in rendering the movement more regular and uniform.

When used in connection with an ordinary rocking-chair, I find the action of my improved appliance is greatly improved by providing means for supporting the feet of the occupant away from the floor, and this I accomplish by extending the forward part of the rockers outward and attaching thereto a foot-rest, F, as indicated in Fig. 1.

My improvement, while herein described and illustrated as being specially applicable to rocking-chairs, is equally applicable to any comfort-giving article having a rocking or swinging motion, such as cradles, &c., and may be so applied without departing from the spirit of my invention.

I make no broad claim in this application to the construction of the equalizing device herein described other than the special applications and combinations herein set forth, such appliance in its other applications being embodied in a separate application filed here-with.

Having thus fully described my invention, what I claim as new, and desire to secure by Letters Patent, is—

1. The combination, with a rocking-chair, of an equalizing device consisting of a tube or track containing a shifting weight or body, essentially as herein described.
- 5 2. The combination, with a rocking-chair having a foot-rest, F, of an equalizing device consisting of a tube or track containing a shifting weight or body, essentially as herein described.
- 10 3. The combination, with a rocking-chair, of a platform, D', equalizing device A B, con-

sisting of a tube or track containing a shifting body or weight, and a spring or springs arranged under the end or ends of the tube or track A, essentially as herein described.

In testimony whereof witness my hand this 10th day of August, 1887.

GEORGE KELLY.

In presence of—

ROBERT BURNS,
M. H. HOLMES,
